ULTRAVIOLET LAMP

Palmer H. Craig, Cincinnati, Ohio, assignor to
Invex Corporation, a corporation of New York

Application May 18, 1933, Serial No. 671,727

7 Claims. (Cl. 176—1)

This invention relates to electric lamps and in particular to lamps for the production of ultra-violet radiations.

While the main object of my invention is to produce a lamp for emitting ultra-violet radiations, a further object is to produce a lamp which may at the same time be employed for illuminating purposes.

A more specific object of my invention is to devise a self-contained ultra-violet lamp provided with a standard lamp base and which may be operated directly from the ordinary 105-120 volt house lighting circuit without the use of special transformers, adapters, or other auxiliary apparatus.

A further object of my invention is to devise an ultra-violet lamp operating on a glow discharge principle and to provide means for ionizing the atmosphere of the lamp upon applying operating current so that the lamp is self-starting, and in which all parts necessary for the operation of the lamp from an ordinary house lighting circuit are incorporated within the lamp structure proper.

My invention is illustrated in the accompanying drawing in which:

Figure 1 is an elevational view of one form of lamp according to my invention;

Figure 1a is an enlarged fragmentary view illustrating features employed in exhausting the lamp shown in Figure 1;

Figure 2 is an elevational view of a second form of lamp according to my invention; and

Figure 3 is an elevational view of a third form of lamp according to my invention.

Referring to Figure 1, the lamp envelope comprises a bulb section 1a and a neck section 1b formed of an insulating material transparent to both visible and ultra-violet radiations, such as quartz, Corex glass, or other special glasses known to the trade. A flare 2 is sealed to the wall of the envelope to hermetically separate section 1a from section 1b, thus forming two hermetically independent compartments in the envelopes. The open end of section 1b is sealed by means of a flare 3, and an exhaust tube 4 is sealed into the press 2a of flare 2 and extends through section 1b, through press 3a of flare 3, to the outside of the envelope. Exhaust tube 4

encloses a wire 5 leading from the tip of screw plug 6 to one end of an incandescent filament 7 mounted within the bulb section 1a, the other end of the filament being connected to a lead wire 8 extending through the press portions of flares 2 and 3. Tube 4 thus serves as an ex-

haust tube for section 1a and as a protective housing to shield wire 5 from the discharge within section 1b. Mounted within section 1b are two electrodes 9 and 10 preferably formed of tubular metallic material such as nickel and coated with an oxide of rare earth metal to increase the electron emission capacity. Mounted within electrodes 9 and 10 are heater filaments 9a and 10a supported from insulating plugs 9b and 10b mounted in each end of the electrodes. The upper ends of heater filaments 9a and 10a are joined by wire 11, while the lower ends of these elements are connected respectively to conductors 12 and 13 sealed into the press 3a. Electrode 9 is electrically connected to the lead wire 15 8, and electrode 10 is connected to lead wire 14 sealed in press 3a. The upper ends of the electrode structures are mechanically supported by wire 11a joined by a glass bead to the upper end of conductor 14.

In manufacturing the lamp shown in Figure 1, I prefer to assemble the entire lamp structure upon the flares 2 and 3 outside of the envelope, the two flares being mechanically connected together by tube 4 and the lower ends of conductors 8, 12, 13 and 14 are left free and unconnected. Tube 4 must not be collapsed while being sealed into press portions of flares 2 and 3. The assembled structure is next inserted within the open end of the envelope and the flares 2 and 3 are then sealed to the envelope, a suitable exhaust tube being provided at the lower end of section 1b. Before placing the lamp structure within the envelope, the tubular electrodes 9 and 10 are coated with a mixture of barium and strontium carbonates (or other suitable solution) which by subsequent treatment is reduced to an oxide state, and to facilitate this reduction process, the conductors 8 and 14 are brought out through press 3a separately from conductors 12 and 13 so that a suitable current may be supplied to the heater filaments to reduce the carbonate without application of a potential to the electrodes.

Section 1a is exhausted by connecting the lower end of tube 4 to the exhaust pump, and, in order to liberate occluded gases from this section of the bulb, it is desirable to energize the filament during the exhaustion process. For this purpose the arrangement shown in Figure 1a is provided. In this figure the elements are shown on a greatly enlarged scale; 4a indicates a glass bead sealed around the wire 5 near the lower end and positioned within the tube 4. Within the end of a rubber tubing 15 connected

to the exhaust pump (not shown) is mounted a spring 15a, on the outer end of which is mounted an iron contact block 15b arranged to make electrical contact with the lower end of wire 5. When the end of tube 4 is pressed over the end of exhaust tube 4, the contact plug 15b enters the end of tube 4 and engages the end of wire 5, the spring 15a serving to insure positive contact between the two elements. If greater pressure is required to maintain contact, a magnet may be arranged above the block 15b with the poles on opposite sides of tube 4 and the magnetic pull on the block 15b will insure positive contact. The lower end of spring 15a is brought out through a glass section 15c of the tube 15 and is connected to a suitable source of current. During the exhaustion process, current is passed through the filament 7 by way of spring 15a and conductor 5 and back to the other terminal of the source by conductor 8, the filament being operated at incandescence to drive out the occluded gases. Upon completion of the exhaustion process, the incandescent section 1a is filled with an inert gas such as argon at substantially atmospheric pressure, and the section is sealed off by collapsing the tube 4 about the bead 4a and sealing the two together. The lower end of the tube 4 is then removed and the end of conductor 5 remains accessible for connection to the tip of the plug either directly or by means of a suitable extension welded thereon.

Section 1b is exhausted in the usual manner by means of an exhaust tube (not shown) in the lower end of the section. Before the section is sealed off a small quantity of mercury is introduced into the section by any suitable method. Upon the completion of the exhausting processes and the process of reducing the coating on the electrodes, the section is sealed off and wires 8 and 12 are joined together at the base of bulb, and wires 13 and 14 are joined together and connected to the sleeve of the plug 6. This completes a circuit from the sleeve of the plug through heater elements 10a, wire 11, heater element 9a, wire 12, wire 8, filament 7 and wire 5 to the tip of plug 6. The filament 7 is designed to absorb all of the voltage drop impressed across the plug except a voltage drop of the order of 15 to 20 volts across the combined resistance of heater elements 9a and 10a. It is to be noted that this voltage drop is impressed between electrodes 9 and 10. The filament 7 is designed to serve as an emitter of visible light as well as to function as a voltage reducer for the electrodes 9 and 10. The resistance of heater elements 9a and 10a is suitably chosen to provide sufficient heat to render the oxide coating on the electrodes thermionically active and to facilitate the establishment of a glow discharge within the section 1b. The heating of the electrodes by the heater elements 9a and 10a facilitates the ionization of the mercury vapor within the section 1b and also serves to activate the oxide coating on the electrodes so that in a short time after the application of current to the lamp a glow discharge is established between the electrodes 9 and 10 which substantially fills the entire section 1b. The lamp is so proportioned that the discharge is substantially that of a diffused glow discharge as distinguished from an arc discharge which concentrates at a particular point or points and is especially destructive to the electrodes. A limited amount of ultra-violet radiation will be produced in section 1a by the incandescent filament and this radiation will be augmented by the

presence of the argon gas, but it will be understood that this gas filling is not essential to my invention and may be omitted.

In the arrangement of the lamp shown in Figure 1 I have placed the filament 7 within the section 1a having the larger radiating surface and located away from the lamp plug in order to facilitate the dissipation of the heat produced by the filament 7, which normally is several times the heat developed by the heater elements 9a and 10a. This is the preferred form of my invention, but it will be understood that the luminous filament 7 may be located in the neck portion 1b and the electrode structures 9 and 10 may be arranged in the bulb section 1a, if desired, and this will be especially feasible where the lamp is designed to have a low current capacity.

It will be seen that the lamp illustrated in Figure 1 is self-contained, self-starting, and will operate upon any commercial supply system without any more attention than is required for an ordinary lamp. The lamp also functions as an illuminating lamp as well as a source of ultra-violet radiations having beneficial effects for many uses.

In Figure 2 I have shown a lamp designed to emit ultra-violet radiations without any substantial luminous or visible radiation. In this form of lamp, there is only one vacuum enclosure 1 for housing the discharge electrodes, and the voltage reducing resistances are arranged within the plug of the lamp outside of the vacuum enclosure. In this form of lamp the two discharge electrodes are formed as concentric cylindrical grid-like electrodes 16 and 17, the outer electrode 16 being preferably formed with a wider mesh than the inner electrode 17. These electrodes may be formed of nickel, iron, or other suitable metal, and are supported from the re-entrant stem 18 by suitable conductors sealed into the press of the stem. Located within the inner cylindrical electrode 17 is an ionizing or heater filament 19 the upper looped end of which is supported by a hook 20 anchored in the glass bead 20a, and the lower ends are supported from conductors 19a and 19b sealed into the press of stem 18. The filament 19 is provided with an oxide coating of the type normally employed for low current capacity vacuum tubes commonly used for radio purposes, such as barium oxide. Conductor 17a supporting the electrode 17 is connected to the shell of the screw plug 6, and the conductor 19a leading to one side of the filament is connected to this conductor outside of the envelope 1. One of the supporting conductors 16a for electrode 16 is connected to one terminal of a resistance element 21 located within the plug 6, and the other end of this resistance element is connected to the tip contact of the plug 6. A second resistance 22 located within the plug 6 has one terminal connected to the same end of resistance 21 as conductor 16, and the other terminal is connected to conductor 19b leading to the filament 19. With the above connections it will be seen that current is supplied from the line to the filament 19 through resistances 21 and 22 connected in series, and the voltage impressed across electrodes 16 and 17 is equal to the combined voltage drop across the filament 19 and resistance 22 and is normally of the order of 15 to 20 volts. The bulb 1 contains a drop of mercury and is also provided with a rare gaseous filling such as neon, helium, argon or similar gases at a pressure to produce a discharge substantially entirely of the negative glow type.

The lamp shown in Figure 2 is normally designed for low power consumption; for example, the filament 19 may be designed to be operated on a current of 30 milli-amperes, and with a glow discharge current of the order of 30 milli-amperes. With these current values, resistance element 21 will be required to dissipate only about 6 watts of energy and resistance element 22 only about one-half watt, assuming a line voltage of 120 volts. The operation of the lamp shown in Figure 2 will be readily understood from the operation of the lamp in Figure 1, it being understood that the filament 19 serves to heat the gas and vapor within the lamp and thereby facilitating the ionization of the vapor and the establishment of a glow discharge between electrodes 16 and 17. This glow discharge is a diffused bluish glow substantially filling the entire envelope 1 and is readily distinguished from an arc or concentrated discharge. If desired, electrode 17 may also be provided with an oxide coating to facilitate the establishment of the glow discharge. This electrode may also be formed of a coated metallic tube as in Figure 1.

In either form of lamp disclosed herein the ionizing filaments, as well as the electrodes, are operated at temperatures below incandescence and are, therefore, not subject to the rapid deterioration which would occur if the filaments were operated at incandescence. Furthermore, in both constructions, the ionizing filament does not serve as one of the electrodes for the ionized discharge established in the lamp, but in both arrangements these filaments are protected from the discharge by an electrode arranged to shield the filaments.

All the filaments employed in the lamps may be made of tungsten, or, if desired, the ionizing filaments may be formed of tungsten, while the filament 1 and resistance 22 may be formed of carbon to offset changes in resistance of the tungsten filaments with changes in temperature and thus prevent a large current upon starting the lamp.

The lamp illustrated in Figure 3 is a modification of the lamp shown in Figure 1. In this arrangement the electrodes 9 and 10 are constructed in the same manner as described above for Figure 1, except that resistance elements 9a and 10a are formed of higher resistance values and serve as current limiting or ballast resistors in the place of the incandescent filament 1 in Figure 1. These electrodes are supported by conductors 9c and 10c sealed in the press of the envelope 1, and the lower end of resistor 9a is connected by wire 12 to the tip of the screw plug, while the lower end of resistor 10a is connected by wire 13 to the sleeve of the plug. The upper ends of the two resistors are connected to their respective electrode sleeves. In constructing this lamp, electrodes 9 and 10 are treated in the same manner as the electrodes for Figure 1, and in order to reduce the carbonate coating to an oxide, the resistor elements are heated by connecting a source of potential between conductors 9c-12 and 10c-13 respectively. When the lamp is completed, the outer ends of conductors 9c and 10c remain free as shown. Electrodes 9 and 10 are also provided with a coating of barium azide (or a tri-nitride of an alkaline metal) in order to establish a glow discharge between the electrodes at impressed voltages of the order of 120 volts. This deposit may be placed on the end portions of the electrodes which are not coated with the oxide, or it may be coated over the oxide coat-

ing. Metallic deposits of magnesium or calcium, or the like, obtained from the gettering process will also serve to establish a discharge at the voltage indicated. Before sealing off the lamp, a small quantity of mercury together with a gaseous filling of neon, argon or helium is introduced into the bulb.

In the operation of the lamp shown in Figure 3, the glow discharge is established as soon as the operating voltage is applied, and resistance elements 9c and 10c serve as ballast resistances to limit the flow of current and also to heat the oxide coating. As the electrodes become heated, the increased electron emission serves to intensify the discharge. It will be noted that the metallic sleeve electrodes 9 and 10 function as protective shields for shielding the ballast resistances from the discharge established between the two electrodes. The portions of conductors 12 and 13 extending between the press and the respective electrodes are provided with insulating sleeves 12a and 13a to prevent the establishment of an arc discharge between these conductors. An effective seal is formed at the ends of these insulating tubes by a filling of magnesia paste. While this construction is not hermetically tight, it is sufficient to prevent the establishment of a discharge between the protected parts. These conductors may be shielded in any other suitable manner as by forming tubes 12a and 13a of metal sleeves having their upper ends crimped around the ceramic plugs in the ends of the electrodes and their lower ends crimped around glass tube extensions surrounding the conductors and sealed into the press.

The lamp shown in Figure 3 may be modified in various ways; for example, the entire ballast resistance may be incorporated within one electrode, in which case the other electrode would not contain a resistance element and may be formed as an open mesh work cylinder surrounding the electrode containing the ballast resistance in a manner somewhat like the arrangement shown in Figure 2. It is also obvious that only one of the electrodes need be provided with the oxide and azide coatings, and the oxide coating may be omitted entirely where an intense discharge is not required. If desired, the azide coating may be omitted and the discharge may be started by providing a resistance filament connected between the electrodes so as to establish a current in the resistance elements 9a and 10a and heat up the oxide coating. This resistance element need not operate at incandescence and should be designed to produce a voltage drop between the electrodes of about 15 to 20 volts.

While I have illustrated lamp constructions provided with standard screw plug bases, any other convenient form of terminal arrangement may be employed.

It will be obvious to those skilled in the art that various modifications in details and general arrangement may be made without departing from the spirit of my invention.

What I claim is:

1. An ultra-violet lamp comprising an envelope formed of material transparent to ultra-violet radiations and having a bulbous section, a neck section and a pair of terminals at the end of the neck section, a flare sealed within said envelope for hermetically separating the bulbous section from the neck section, said neck section being provided with an ionizable atmosphere, a pair of spaced electrodes mounted within said neck section, a heater filament mounted within said

- neck section, an incandescent filament mounted in said bulbous section, connections from said terminals for energizing said heater filament and incandescent filament in serial circuit relation and for establishing a discharge between said electrodes, said connections including a conductor passing through said neck section and connecting one of said terminals to one end of said incandescent filament in the bulbous section, and 10 means for insulating said conductor from the ionized discharge in said neck section.
2. An ultra-violet lamp comprising an envelope formed of material transparent to ultra-violet radiations and having a bulbous section, a neck section and a screw plug at the end of the neck section, a flare sealed within said envelope for hermetically separating the bulbous section from the neck section, an exhaust tube sealed in said flare and passing through said neck section and terminating within said screw plug, means for establishing an ionized discharge in said neck section, an incandescent filament mounted within said bulbous section, and circuit connections from said screw plug to said filament including a conductor arranged within said exhaust tube.
3. An ultra-violet lamp comprising an envelope formed of material transparent to ultra-violet radiations and having a bulbous section, a neck section and a screw plug at the end of the neck section, a flare sealed within said envelope for hermetically separating the bulbous section from the neck section, said neck section being provided with an ionizable atmosphere, a pair of spaced electrodes mounted within said neck section, a heater filament mounted within said neck section and connected across said electrodes, an exhaust tube sealed in said flare and passing through said neck section and terminating within said screw plug, an incandescent filament mounted within said bulbous section, and circuit connections from said screw plug connecting said filaments in serial circuit relation including a conductor arranged within said exhaust tube.
4. An ultra-violet lamp comprising an envelope formed of material transparent to ultra-violet radiations and having a sealed compartment in the bulbous section, a second sealed compartment in the neck section and a screw plug at the end of the neck section, means for establishing an ionized discharge in the second sealed compartment, an exhaust tube for the first sealed compartment passing through said second compartment and terminating within said screw plug, an incandescent filament mounted within said first compartment, and circuit connections from said screw plug to said filament including a conductor arranged within said exhaust tube.
5. An ultra-violet lamp comprising an envelope formed of material transparent to ultra-
- violet radiations and having a sealed compartment in the bulbous section, a second sealed compartment in the neck section and a screw plug at the end of the neck section, said second sealed compartment being provided with an ionizable atmosphere, a pair of spaced electrodes mounted within said second sealed compartment, a heater filament mounted within said second sealed compartment and connected across said electrodes, an exhaust tube for said first sealed compartment passing through said second sealed compartment and terminating within said screw plug, an incandescent filament mounted within said first compartment, and circuit connections from said screw plug connecting said filaments in serial circuit relation including a conductor arranged within said exhaust tube.
6. An ultra-violet lamp comprising a single envelope formed of material transparent to ultra-violet radiations and having a bulbous section and a reduced cylindrical neck section with a screw plug mounted at the end of the neck section, a partition sealed within said envelope for separating the bulbous section from the cylindrical neck section to form hermetically separate compartments, an exhaust tube for said bulbous section passing through said neck section and terminating in said screw plug, one of said compartments containing an ionizable atmosphere and having mounted therein a pair of spaced electrodes with a heater filament connected across the same, the other compartment having an incandescent filament mounted therein, and circuit connections from said screw plug connecting said heater filament and incandescent filament in serial circuit relation.
7. An ultra-violet lamp comprising a single envelope formed of material transparent to ultra-violet radiations and having a bulbous section and a reduced neck section with a screw plug mounted at the end of the neck section, a partition sealed within said envelope for separating the bulbous section from the neck section to form hermetically separate compartments, said neck compartment being provided with an ionizable atmosphere, a pair of spaced electrodes mounted within said neck compartment, a heater filament mounted within said neck compartment and connected across said spaced electrodes, an incandescent filament mounted in said bulbous compartment, circuit connections for connecting said heater filament and said incandescent filament in serial circuit relation across the elements of said screw plug, said connections including a conductor passing through said neck compartment and connecting one end of the incandescent filament with one element of said plug, and means for insulating said conductor from the ionized discharge in said neck compartment.

PALMER H. CRAIG. 60
